FOREIGN PATENT DOCUMENTS

CN 306956108 * 11/2021

Primary Examiner — Marie D. Fast Horse

(57) **CLAIM**

The ornamental design for a scan code payment terminal as shown and described.

DESCRIPTION

1. Scan code payment terminal

1.1: Front

1.2: Back

1.3: Left

1.4: Right

1.5: Top

1.6: Bottom

1.7: Perspective

The broken lines in the drawings depict portions of the scan code payment terminal that form no part of the claimed design.

1 Claim, 7 Drawing Sheets(56)
